US00D612512S

(12) **United States Design Patent**
Stevens et al.

(10) **Patent No.:** US D612,512 S
(45) **Date of Patent:** ** Mar. 23, 2010

(54) **HEATABLE HOUSING FOR CONTACT LENS CONTAINERS**

(75) Inventors: **Dale Stevens**, Spence (AU); **Blake Stevens**, Palmerston (AU)

(73) Assignee: **Qirx Pty Ltd.**, Mitchell Australian Capital Territory (AU)

(**) Term: **14 Years**

(21) Appl. No.: **29/328,607**

(22) Filed: **Nov. 26, 2008**

(30) **Foreign Application Priority Data**

May 27, 2008 (AU) 12544/2008

(51) **LOC (9) Cl.** 24-02

(52) **U.S. Cl.** D24/218

(58) **Field of Classification Search** D3/263-264; D24/218; D16/331; 206/5.1

See application file for complete search history.

(57) **CLAIM**

We claim the ornamental design for a heatable housing for contact lens containers, as shown and described.

DESCRIPTION

FIG. 1 is a left side elevational view of a heatable housing for contact lens containers showing our new design.

FIG. 2 is a rear elevational view thereof.

FIG. 3 is a top elevational view thereof;

FIG. 4 is a front elevational view thereof;

FIG. 5 is a bottom plan view thereof;

FIG. 6 is a right-side elevational view thereof;

FIG. 7 is a front perspective view thereof; and,

FIG. 8 is a rear perspective view thereof.
